UNITED STATES PATENT OFFICE.

GEORGE H. CORLISS, OF PROVIDENCE, RHODE ISLAND.

STEAM-BOILER.

SPECIFICATION forming part of Letters Patent No. 333,833, dated January 5, 1886.

Application filed June 13, 1885. Serial No. 168,595. (No model.)

To all whom it may concern:

Be it known that I, GEORGE H. CORLISS, a citizen of the United States, residing in the city and county of Providence, in the State of Rhode Island, have invented a certain new and useful Improvement in Steam-Boilers, of which the following is a specification.

The object is to provide efficiently and conveniently for the circulation of water downward in the narrow space around the furnaces of boilers having furnaces in their interiors.

I will describe the invention as applied to an upright boiler of cylindrical form with a corresponding cylindrical furnace and a space between it and the shell or exterior of the boiler. I provide a set of tubes, open at each end and of sufficient length to extend up and down nearly or quite the whole height of the furnace, and secure them in the required positions to provide for downward circulation in the water-leg. In the spaces between and around these tubes the water moves upward, being largely filled with steam, which is being actively generated by the heat of the furnace.

The accompanying drawings form a part of this specification, and represent what I consider the best means of carrying out the invention.

Figure 1 is a horizontal section, and Fig. 2 a vertical section, of a boiler having my invention.

Similar letters of reference indicate corresponding parts in both the figures.

A is the outer portion or shell, and B the inner portion or furnace. B' is the crown or top of the furnace, and C the ordinary upright tubes which convey the gaseous products of combustion upward from the furnace. All these parts may be as usual. Each upright tube D is of a diameter something less than the thickness of the water leg or space between

A and B, and is cut away at each end to form a securing-lip, d. Each is riveted to the shell A by rivets E, which pass through the lips d, and stands with its upper end somewhat above the crown-sheet E', and its lower end a little above the bottom of the water-leg. The current of water forced upward by the volume of steam generated in the water-leg is supplied by a freely-descending series of currents in the several tubes D. While in the ordinary water-leg the dense water will travel only part way down the leg before returning, my invention insures a thorough and complete circulation of the water clear to the bottom of the leg, and tends thereby to keep the leg free from the deposit of sediment.

Modifications may be made in the forms and proportions.

The tubes D may be of less thickness, and may be held by smaller rivets than shown. A greater or less number may suffice. They may be distributed irregularly, if preferred in any case.

I claim as my invention—

In a steam-boiler having an internal furnace, a series of tubes, as D D, extending up and down in the space between the furnace and shell, open at each end and cut away to form lips d, the tube D being secured to the shell A by fastenings E, which pass through said lips, all arranged for joint operation substantially as herein specified.

In testimony whereof I have hereunto set my hand, at Providence, Rhode Island, this 2d day of June, 1885, in the presence of two subscribing witnesses.

GEORGE H. CORLISS.
